A. Todd Jr.

United States Patent Office.

ASAHEL TODD, JR., OF PULTNEYVILLE, NEW YORK, ASSIGNOR TO HIMSELF,
A. F. SHELDON, J. S. TODD, T. S. LEDYARD, AND L. S. CUYLER.

Letters Patent No. 74,018, dated February 4, 1868.

IMPROVEMENT IN THE CONSTRUCTION OF FENCE.

The Schedule referred to in these Letters Patent and making part of the same.

TO WHOM IT MAY CONCERN:

Be it known that I, ASAHEL TODD, Jr., of Pultneyville, Wayne county, New York, have invented new and useful Improvements in the Construction of Fence; and I do hereby declare that the following is a full and exact description thereof, reference being had to the accompanying drawings, making a part of this specification, in which—

Figure 1 shows the invention, used in constructing wire and picket-fence.

Figure 2 is a perspective view of the same, without the guides.

Similar letter of reference refer to like parts in the several figures.

The double-acting jointed lever D, figs. 1 and 2, is made of wood or iron, with sufficient curve in the middle section to allow the short arms E E' to fold parallel with the middle section J. The short arms E E' are pivoted to the middle section J, and articulate upon a bolt or pin passing through the arms E E', and middle section J, at F F'. When it is desirable to build field-fences rapidly, without using a line to set the pickets at a uniform height, the guide I is bolted to the side of the upper arm E, to retain the lever at right angles with the wires, and the indexes H H' are secured, at proper distances apart, upon the upright standard L, which is nailed or bolted to the middle section J, fig. 1. The short arms E E' are notched at K K', fig. 2, to hold the lever in position upon the wires.

To enable others to make and use my invention, I will describe its operation.

The posts A are set in the ground in the usual manner. The wires B B' are fastened to the posts, at proper distances apart, to permit the lever D to be worked without changing the relative position of the wires upon the posts. The short arms E E' and guide I, fig. 1, are placed between the parallel wires B B', with the short arm E folded to the middle section, the short arm E' erect. Now introduce a picket, the top of which should be even with the index H'. Drive the picket tight, then, with the hand, grasp the middle section D, and draw it from the wires and downwards; this will cause the wires to cross, as shown by the dotted lines, fig. 1. The next picket, M, is now introduced, the top of which should be even with the index H, shown in fig. 1 by dotted lines.

What I claim, and desire to secure by Letters Patent, is—

1. The jointed double-acting lever D.
2. The detachable indexes K and H H', in combination with the double-acting lever D and guide I.
3. The detachable guide I, in combination with the lever D and indexes K and H H', substantially and for the purposes set forth.

Witnesses:

THOS. A. CONNOLLY,
EDM. F. BROWN.
